(57) **CLAIM**

The ornamental design for a specimen collecting device, as shown and described.

DESCRIPTION

FIG. 1 is a top plan view of a specimen collecting device showing my new design;

FIG. 2 is a bottom plan view thereof;

FIG. 3 is a front view thereof;

FIG. 4 is a rear view thereof;

FIG. 5 is a left side view thereof;

FIG. 6 is a right side view thereof;

FIG. 7 is a perspective view thereof; and,

FIG. 8 is another perspective view thereof.

The broken lines in the drawings depict portions of the specimen collecting device that form no part of the claimed design.

The broken lines in the drawings and the areas within them depict portions of the probe for an ultrasonic diagnosis apparatus that form no part of the claimed design.
